UNITED STATES PATENT OFFICE.

CHARLES W. EICHLING, JR., OF MEMPHIS, TENNESSEE.

STORAGE AND DISPLAY STAND.

1,303,185.

Specification of Letters Patent.

Patented May 6, 1919.

Application filed August 7, 1918. Serial No. 248,734.

To all whom it may concern:

Be it known that I, CHARLES W. EICHLING, Jr., a citizen of the United States, residing at Memphis, Shelby county, and 5 State of Tennessee, have invented and discovered certain new and useful Improvements in Storage and Display Stands, of which the following is a specification.

My said invention relates to storage and 10 display stands for perishable products and consists in the combinations and arrangement of elements hereinafter described and particularly set forth in the accompanying claim.

15 The purpose of the invention is to provide an apparatus for storage and displaying vegetables, flowering plants and other easily perishable products in such a manner that the same will be kept fresh and salable for 20 prolonged periods, and in such a way that the same may be frequently sprinkled with water and to provide for subjecting such products to the free circulation of air.

Another purpose of the invention is to 25 construct a display and storage stand with the holders thereof arranged in tiered compartments to the end of easy accessibility and convenient grouping of the articles and handling the groups without interference 30 with each other.

The invention is shown by way of illustration in the accompanying drawing, wherein,

35 Figure 1 is a perspective view of the stand complete,

Fig. 2, a transverse sectional view thereof, and

Fig. 3, a detailed perspective view of the 40 apron or water shed.

Referring to the construction in further detail and wherein like reference characters 45 designate corresponding parts in the different views shown, the stand consists of a suitable supporting framework having the front and rear legs 4 and 5 thereof of relatively different height, as shown, and each of said legs has a caster or roller 6 whereby the stand may be readily moved from place to place.

50 A plurality of shelves 7 are arranged in tiers or step formation and a top shelf 8 serves for supporting plants in pots or other goods on display. The front walls or portions 9 of the several shelves form compa-

ments or receptacles of the several steps and 55 end boards 10 close said compartments at either end of the stand as shown.

The rear portion of each bottom wall 7 and the immediately adjacent portion of the rear wall of each compartment is left open, 60 and a strip of wire mesh screen 11 or other appropriate perforated material is laid thereover for the full length of the stand thereby giving free air passage for ventilating the plants or vegetables on display or 65 in storage.

Each shelf or support is provided with a number of partitions 20 to provide separate compartments for holding the plants in different stages of growth or different kinds 70 of plants, and said compartments are readily removable to the end of accommodating plants of different sizes. The screen sections 11 also allow the plants to be watered by sprinkling and to this end an apron or 75 water shed is provided to catch the overflow and direct the same to a suitable receiver or drip can 12. Said apron consists preferably of a sheet of metal 13 mounted on an incline and having cut away rear portions 14 80 forming a flange 15 by means of which the apron is secured to the stand. The lower edge of the apron has an up-turned flange 16 for collecting the water and is formed 85 with a depressed portion 17 leading to an outlet 18 disposed immediately over the can 12 as shown.

In use the root portions of the plants are laid in layers on a foundation of damp sphagnum, moss or other moisture retaining 90 substance that covers the screen sections 11; and these layers of plant roots resting on mosses may be placed in the several compartments one upon the other without harm. In this condition the plants or other articles 95 may be watered at the necessary intervals for keeping the same in proper condition and inasmuch as all excess water will run off it is obvious that the articles may be kept in prime condition for prolonged periods and without liability of rotting or 100 the deteriorating effects caused by mildew.

Having thus fully described my said invention, what I claim as new and desire to secure by Letters Patent, is:

105 A storing and display stand for plants comprising supporting legs, tiers of receptacles mounted thereon and having adjoin-

ing portions of their respective bottom and rear walls open and covered with wire screen, and an inclined sheet of metal carried by said supporting legs beneath said 5 receptacles and providing a watershed, substantially as set forth.

In witness whereof I have hereunto set

my hand and seal at Memphis, Tennessee, this 2nd day of August, A. D. nineteen hundred and eighteen.

CHARLES W. EICHLING, JR. [L.S.]
Witnesses:

D. D. WILLIAMS,
JOHN W. FARLEY.
